Letters Patent No. 77,076, dated April 21, 1868.

IMPROVEMENT IN WRENCH.

The Schedule referred to in these Letters Patent and making part of the same.

TO ALL WHOM IT MAY CONCERN:

Be it known that I, IR A M O R S E, of Danbury, in the county of Fairfield, and State of Connecticut, have invented a new and useful Improvement in Wrenches; and I do hereby declare the following to be a full, clear, and exact description of the same, reference being had to the accompanying drawings, in which—

Figure 1 is a side elevation of my wrench, with the slide-nut and handle in section.

Figure 2 is a front elevation of the same, with nut and handle in section.

My improvement relates to that class of screw-wrenches which are designed to be applied to the turning of screw-nuts or pipes; and my invention consists, mainly, in the construction of the jaws, whereby, when using as a pipe-wrench, no resetting of the jaws will be required in changing from one pipe to another of the same size.

That others may fully understand my invention, I will particularly describe it.

A is the bar of the wrench, the upper end of which is turned over edgways to form the head or upper jaw B. Upon the bar A the sliding case C is fitted, so that it may move snugly but freely up and down thereon. The sliding case C carries the movable or lower jaw D. At the lower end of the bar A commences the shank E, which passes downward through the ferrule F and handle G, and is secured therein by the screw-nut H. At the point of junction between the bar A and shank E, the shoulders a a are formed by the rounding off of the corners, and, if desired, otherwise reducing the size of the bar. The case C is provided, at its lower end, with two slabs, I I, of a screw, about equal in diameter to the largest diameter of the bar A. These slabs, I I, are rigidly attached to the case C, and have a space between them just equal to the thickness of the bar A, so that the said slabs lie against the side of A when in position, and move up and down in contact therewith. The screw-nut J is fitted to the screw-thread on the slabs I I, and when all of the parts are in position said nut is confined between the shoulders a a and the ferrule F, and is thereby restrained of any lateral motion, but may move freely around its axis; and by said motion the slabs I I and the case C are caused to move up or down on the bar A, to open or close the jaws B D.

The jaw D is pivoted to the case C, as shown at b, so as to permit it to have slight movement to or from the bar A and jaw B; and there is inserted behind it, in any convenient way, a spring, K, to keep the said jaw always open when not in use. This spring may be of rubber or metal, and may be inserted at any point where it can have the desired action.

The jaws B D are constructed so that when the latter one is thrown open by the spring K, they are divergent from each other, from the back to the front, and if they are set at the proper distance apart, any cylindrical body of the proper size may be inserted between them and instantly gripped without changing the screw-nut J, because, if the body will enter between the outer edges of the jaws, it may be inserted until it is in contact with both of them, and then a slight movement of the handle G in the proper direction causes the jaw D to move on its pivot and gripe the body between the jaws in the manner familiar to all persons who use pipe-wrenches. And when the wrench is to be removed from the pipe, a contrary motion of the handle G releases it from the pressure of the jaw D, and it may be freely removed.

I am aware that wrenches have been made with sliding cases and movable jaws, said jaws having springs set behind them, as in the wrenches patented by Bartholomew and Merrick, January 2, 1849; Stillson and Chapman, 31st October, 1865, and others; but in said wrenches, and in all others, so far as I am aware, the pipe to be gripped could not be inserted between the jaws until the movable jaw had been opened by the screw, nor the pipe gripped until the jaws have been closed again by the screw, and that this process had to be repeated to remove the wrench; in other words, the distance between the outer edges of the two jaws was made less than the distance between points within the outer edges. In my wrench the distance between the outer edges is the greatest distance, and the pipe can therefore be inserted or removed without changing the position of the case upon the bar of the wrench. This facility of attachment and removal is of great importance, as saving much time and trouble.

Having described my invention, what I claim as new, is—

A wrench, having the bar A, serrated rigid jaw B, and hinge serrated jaw D, attached to the sleeve C, both jaws being divergent outward, and all constructed and arranged substantially as described.
